UNITED STATES PATENT OFFICE.

DAN L. HILL, OF WEST SWANZEY, NEW HAMPSHIRE.

MACHINE FOR MAKING WIRE HINGES.

SPECIFICATION forming part of Letters Patent No. 411,194, dated September 17, 1889.

Application filed February 13, 1889. Serial No. 299,798. (No model.)

To all whom it may concern:

Be it known that I, DAN L. HILL, a citizen of the United States, residing at West Swan-
5 zey, in the county of Cheshire and State of New Hampshire, have invented new and useful Improvements in Machines for Making Wire Hinges for Boxes, of which the following is a specification.

My invention relates to improvements in
10 machines for making wire hinges for boxes and other articles; and it consists in the peculiar construction and combination of devices that will be more fully set forth hereinafter, and particularly pointed out in the
15 claims.

In the accompanying drawings, Figure 1 is a perspective view of a machine embodying my improvements. Fig. 2 is a side elevation of the same. Fig. 3 is a sectional view taken
20 on the line $x-x$ of Fig. 4. Fig. 4 is a top plan view. Fig. 5 is a sectional view taken on the line $y-y$ of Fig. 4. Fig. 6 is a sectional view taken on the line $z-z$ of Fig. 4. Figs. 7, 8, 9,
25 10, and 11 are detailed perspective views illustrating the positions of the clamping-jaws and bending finger or arm during different stages of the operation of the machine. Fig. 10^a is a view showing the parts in same relative position as in Fig. 10, but from the
30 opposite side, so as to expose the construction more clearly. Fig. 12 is a top plan view of the machine with the yoke X^2 and all its parts removed, so as to expose the mechanism lying under said yoke. Fig. 13 is a view
35 of the under side of the yoke X^2 and the parts carried by said yoke. Fig. 14 is a perspective view of the two pairs of bending-clamps and their operating mechanism detached from the rest of the machine. Fig. 15 is a perspective
40 view of one of the wire hinges produced by my improved machine.

Near one side of a bed-plate A are secured a pair of standards B, in which is journaled the driving-shaft C, which is provided with
45 an offset portion or crank D. To one end of the said shaft is secured a driving-wheel or belt-pulley E; or said shaft may be provided with a hand-crank F, if preferred, and to the opposite end of the shaft is secured a miter-
50 wheel G. A tappet-arm H projects from the said shaft, near one of its ends, and to the

offset or crank portion of the shaft is keyed a miter-wheel I. Arranged at right angles to the bearings or standards B are a pair of standards K, in which is journaled a shaft L, 55 having a miter-wheel M on its inner end, which engages the miter-wheel G'; hence rotary motion of the shaft C is communicated to shaft L.

N represents a tappet-bar, which is arranged 60 transversely on the shaft L, and is keyed thereto, and is provided at opposite extremities with right-angled tappet-arms O P, which extend in opposite directions. Also keyed to the shaft L and arranged adjacent to the tappet-bar is a cam R. A feed-roller S is keyed to said shaft and has a gear-wheel T at its inner end, and also secured to the shaft L and arranged at an angle of about fifteen degrees with relation to the tappet-bar N is an 65 arm U, which has a beveled or inclined face V at its outer end on its inner side.

A standard W is secured to the bed-plate and has an arm X at its upper end, which extends over the feed-roller S, and is bifurcated at its outer end to form a pair of ears, between which is journaled a feed-roller Y, 75 which is arranged above the feed-roller S and adjacent to the same, and has a gear-wheel Z at its inner side, which engages the gear T. 80 A spring plate or arm A' is bolted to the upper end of the adjacent standard K and rests on the arm X, the function of the said plate being to exert constant downward pressure on the arm X and prevent the same from 85 swinging upward.

B' represents a wire-guide, which is arranged at right angles to the shaft L and is supported by a pair of standards C'. Said wire-guide has its inner end in proximity to 90 and in the same plane with the space between the feed-rollers, and is provided with a longitudinal opening D', which extends throughout its entire length. A longitudinal slot E' 95 in the side of and at the outer end of the wire-guide communicates with the outer end of the longitudinal opening D', as shown.

F' represents a sigmoidal-shaped lever, which is pivoted on the under side of the wire-guide by means of a pivotal bolt G'. One 100 end of the said lever is normally arranged in the path of the tappet-arm U, and is provided

on its outer side with a beveled face or cam H', adapted to be engaged by the face or cam V of said tappet-lever. A cutter I' is guided in a transverse opening in the wire-guide at 5 a suitable distance from the outer end thereof, and is connected to the outer end of the lever F' and is adapted to be operated thereby. On the outer side of the wire-guide is secured a flat spring K', the free end of which 10 is adapted to engage the end of the cutter, and is provided with a notch which registers with the slot E'.

Secured to the upper end of a standard L' and arranged in line with and at a suitable distance from the outer end of the wire-guide is 15 a box M', which is open on its inner end and on its outer side. Secured also to the upper end of the standard L' is a horizontal stationary jaw N', which is arranged at right 20 angles to the wire-guide.

A lever O', pivoted between a pair of ears P', secured on the base, has an arm R' rising from its inner end and is provided with a movable jaw S', adapted to play laterally 25 toward and from the rigid jaw N', and at the outer end of the lever O' is formed a tappet T', which is adapted to engage the cam R, whereby the said lever, and consequently the movable jaw, is adapted to be operated by 30 said cam, as will be readily understood. A spring U' extends from the base-plate or bed to the lever O' and draws downward on the same.

V' represents a standard secured on the 35 bed-plate near the ears P', and fulcrumed to the said standard are a pair of levers W' and X', the outer ends of which are offset in opposite directions and adapted to be engaged, respectively, by the tappet-arms O P. A 40 spring Y' bears downward on the outer end of lever X', and a spring Z' presses upward under the outer end of lever W'. The said levers W' and X' are provided at their inner ends with slots A² B², respectively.

C² represents a guide-bar, which is secured 45 on the base-plate or bed and is arranged in the position at right angles to one of the standards B and in proximity thereto.

D² represents a right-angled bar, which has 50 arms E² F² extending in opposite directions and guided in a block G² and in the block C², respectively. The arm F² has its outer extremity reduced and made cylindrical in shape.

H² represents a yoke or standard, which 55 is pivoted on the extended part of arm F² and is adapted to partly turn thereon and to move longitudinally therewith. Formed at the upper end of said yoke or standard, or secured thereto and projecting inward therefrom, is a block I², which is provided with a 60 pair of vertical openings arranged at a suitable distance apart. From the arm E² of the bar D² project a pair of vertical standards or tappet-arms K² L², which are arranged on opposite sides of and at a distance from the driving-shaft C, and are adapted to be alternately engaged by the tappet-arm H of the

said shaft, whereby the rotation of the latter will cause intermittent reciprocating motion to be imparted to the bar D² and the standard or yoke H², and hence the latter will be moved alternately toward and from the standard L'. A spring M² is secured to the base-plate or bed and its free end bears against the outer side of standard or yoke H². 75

N² represents a right-angled bar or rod, which has its upper end mounted to slide vertically in the block I² and has its lower horizontal arm engaging the slot B² of the lever X'. 80

O² represents a similar right-angled bar, which has its vertical arm extending through and adapted to move in one of the openings in the block I² and has its horizontal arm engaging the slot A² of the lever W'. From the 85 upper side of the block I² projects a vertical guide-arm P².

R² represents a block or jaw, which is rigidly secured to the upper end of the bar O² and has an opening through which the guide-arm P² extends. Thereby the said block or jaw R² is adapted to move vertically toward and from the block I² when the lever W' is operated. 90

S² represents a standard, which has a pair 95 of arms T² at its upper end and rises from the base-plate, and is located at suitable distance in rear of the block I² and the jaw on the wire-guide.

U² represents a pair of vertical standards 100 which rise from the base-plate and have their upper ends bifurcated, and in the said bifurcated extremities of the standards are pivoted guides V².

W² represents a U-shaped yoke, which has 105 its arms engaging the guides, and to the rear transverse side of the yoke is bolted a bar X². The outer end of the bar X² is pivoted to the offset or crank D, and said bar is provided with a pair of right-angled arms Y². 110

Z² represents a shaft, which is journaled in bearings in the said arms, and to one end of the said shaft is keyed a miter-wheel A³, which engages the miter-wheel I. Projecting at right angles from the said shaft is an arm 115 B³, the outer end of which is beveled on one side to form a cam. To the outer end of the shaft Z² is keyed a crown-wheel C³.

D³ represents a plate, which is bolted to the under side of the transverse portion of yoke 120 W² and projects forward therefrom. Depending from the outer end of the said plate is a longitudinally-perforated arm or wire-guide E³, which has a finger or point F³ at its lower end, and bolted to one side of the said arm 125 and projecting forward therefrom is a downwardly-curved hook G³. Also depending from the plate D³ at one side of the same is an obliquely-arranged cam H³, which is adapted to engage the upper end of the guide-arm P² and thereby move the standard H² outward against the tension of the spring M², when the yoke 130 is moved inward by the bar X² and the offset crank.

Bolted near the outer end of the bar X^2 is an inverted-U-shaped arm I^3 , the lower outer end of which is bifurcated and provided with bearings, in which is journaled a feed-roller 5 K^3 . The same is provided on one side with a gear-wheel, which meshes with a similar gear formed on the feed-roller L^3 . The latter is journaled on a spindle, that projects rearward from a standard M^3 , said standard rising from the front end of plate D^3 . On the rear side of the feed-roller L^3 is a crown-wheel O^3 , which engages the crown-wheel C^3 .

P^3 represents a guide-arm, which is bolted to the outer end of the bar X^2 and projects 15 transversely therefrom over the feed-rollers $L^3 K^3$. Said guide-arm has an opening in its outer end in vertical alignment with a similar opening in the plate D^3 and with the vertical longitudinal bore in the arm E^3 , which 20 arm constitutes a wire-guide that is similar in construction to the wire-guide B' .

R^3 represents a cutter, which works in a transverse opening in the wire-guide E^3 , and is also supported by a guide S^3 , which is bolted 25 to the lower side of the plate D^3 . A plate T^3 is guided in arms U^3 , which project from the bar X^2 , the longitudinal movement of said plate being limited by pins or screws W^3 , which extend through openings in the guide- 30 arms and work in slots X^3 of the plate. The latter has a shoulder Z^3 , which is adapted to be engaged by the cam-arm B^3 on the shaft Z^2 and moved in one direction thereby, and a spring A^4 presses against the rear end of the 35 said plate and moves the same normally forward. A link B^4 connects the plate with the cutter R^3 and serves to communicate the motion of the plate to the said cutter.

C^4 represents a flat spring, which is secured 40 to the bar X^2 and bears against the rear end of the cutter, the same serving to force the cutter normally forward.

D^4 represents a guide-arm, which has an eye E^4 , through which a wire a from a suitable coil extends, the said wire also passing 45 through guide-openings F^4 in the arm W and being directed between the feed-rollers $S Y$ and into and through the longitudinal bore of the guide B' .

G^4 represents a guide-yoke, which is secured 50 to the base-plate in a position at right angles to the guide-arm D^4 , and is provided with a series of eyes H^4 , through which a wire b is passed, the said wire being then passed 55 through the guide-opening in the arm I^4 and in plate D^3 , between the feed-rollers $L^3 K^3$, and into and through the longitudinal bore of the wire-guide arm E^3 .

The operation of my invention is as follows: 60 At the initial movement of the driving-shaft the rollers $S Y$ move the wire a through the guide B' and cause the end thereof to enter the box M' , the said wire being thereby arranged at right angles to the path traversed 65 by the finger at the lower end of guide-arm E^3 and across the outer ends of the rigid jaw N' . While the wire a is being thus fed to the

box, the wire b is moved downward by the feed-rollers $K^3 L^3$, which are rotated by being geared together and to the shaft Z^2 , which is 70 geared to the miter-wheel on the crank or offset of the driving-shaft, and continued rotation of the driving-shaft causes the finger at the lower end of the guide-arm E^3 to come in contact with the intersecting portions of the 75 wires $a b$.

By this time the tappet-arm on the shaft I , engages the lever F' and causes the same to operate the cutter G' , and cause the latter to sever the wire a and leave the severed portion thereof in contact with the finger. The 80 cam R , by operating the lever O' , causes the jaw S' to move toward the rigid jaw N' after the finger has passed between the opposing sides of said jaws and bend the severed portion of the wire a into the form of a staple until said jaw 85 S' closes against the rigid jaw N' and thereby clinches the said portion of the wire a .

While the arm or wire-guide E^3 is moving rearward between the jaws $S' N'$ and bending the wire a , the tappet-arm on the shaft C 90 is in engagement with the tappet-arm L^2 of bar D^2 and moves said bar forward, together with the standard H^2 , and the cam H^3 , by engaging the guide-arm P^2 , moves the standard H^2 outward against the tension of the spring 95 M^2 , thereby causing the jaws carried by the said standard to move out of the path traversed by the wire-guide E^3 .

At the instant that the said cam H^3 clears the guide-arm P^2 the spring M^2 swings the standard H^2 inward, so as to cause its rigid jaw I^2 and vertically, movable jaw R^2 to move in front of the wire b and become engaged therewith. The cutter in the guide-arm E^3 is at this instant operated by the mechanism previously described and caused to cut the wire b , and the offset in the shaft C in rising moves the bar X^2 and the yoke and mechanism connected therewith forward, thereby returning the guide-arm E^3 to its initial position in front of the jaws N' and S' . Owing 105 to the space between the tappet-arms $K^2 L^2$ of the bar D^2 the said bar remains stationary, together with the standard H^2 and the jaws $I^2 R^2$, while the tappet-arm H of shaft C is 110 moving rearward to the tappet-arm L^2 . As said tappet-arms come in contact, continued rotation of the driving-shaft causes the bar D^2 to move rearward, and thereby the jaws $I^2 R^2$ move rearward under and over the jaws 115 $N' S'$, between which the wire a remains clinched and which serve to bend the severed portion of the wire b in the bent portion of the wire a , thereby linking the said bent wires together. Owing to the concentric face 120 of the cam R , the lever O' remains stationary during this movement of the bar D^2 , and its attachments, and consequently the jaw S' , remains clinched against the jaw N' .

While the bar D^2 and the jaws or blocks $I^2 R^2$ are 125 moving rearward the right-angled bars N^2 and O^2 move idly through the slot Z' of lever X' and through the slot A^2 of lever W' , respectively, and when the bar D^2 reaches the 130

inward limit of its stroke the blocks or jaws I^2 and R^2 are entirely clear of and in rear of the jaws $N' S'$. The tappet-arm O then engages the lever W' and raises the outer end 5 thereof, causing its inner end to depress the bar O^2 and consequently lower the block or jaw R^2 . At the instant that the lever W' becomes engaged by the arm O the lever X' becomes engaged by the arm P , and while the block R^2 is being lowered, as before stated, 10 the said lever X' and the right-angled bar N^2 cause the jaw I^2 to rise, and thereby said jaws I^2 and R^2 close together on the bent arms of the wire b and clinch the same together, thus 15 completing the operation of making a hinge. As the geared shafts continue to revolve, the arms $O P$ slip from the levers $W' X'$ and the cam R slips from the tappet T' of lever O' simultaneously, and the springs connected to 20 the said levers open the jaw S' from the jaw N' and open the jaws $I^2 R^2$ simultaneously by returning the said levers to their initial positions, and consequently the hinge is released 25 and drops by gravity through a vertical spout c , which extends through an opening in the base or bed plate.

It will be understood from the foregoing that the operation of making the wire hinge is completed at a single rotation of the driving-shaft. The hook G^3 , which depends from 30 the plate D^3 , by following in rear of the arm E^3 , engages the next succeeding portion of the wire a , which is fed forward through the wire-guides B' , and partly bends the same and 35 leaves it in position to be engaged by the finger of the arm or guide E^3 on the next successive movement of the latter.

Having thus described my invention, I claim—

40 1. The combination, with the feeding mechanisms, of the rigid jaw N' , the movable jaw S' , the jaws $I^2 R^2$, arranged at right angles to the jaws $N' S'$, and the finger to move between the jaws $N' S'$, for the purpose set forth, 45 substantially as described.

2. The combination, in a machine for making wire hinges, of the movable arm or wire-guide E^3 , having finger F^3 , the jaws arranged in the path of the latter and adapted to be 50 clamped together, and the movable clamping-jaws adapted to follow the wire-guide and finger, substantially as described.

3. The combination of the clamping-jaws, the feeder to direct a wire across one end of 55 the same, and the wire feeder or guide arm having a finger adapted to move between the opposing sides of said jaws and thereby bend the wire into **U** form, substantially as described.

60 4. The combination of the pair of clamping-jaws, the feeder to direct a wire across one end of the same, the cutter to sever the wire, and the wire feeder or guide arm having a finger adapted to move between the opposing 65 sides of said jaws, for the purpose set forth, substantially as described.

5. The combination of the stationary pair

of clamping-jaws, the bending arm or finger to pass between them, and the pair of movable clamping-jaws traveling across the stationary jaws and in rear of the bending arm or finger, substantially as described. 70

6. The combination of the driving-shaft having the crank, the counter-shaft geared thereto and having the cams, the feed-rollers 75 operated by said counter-shaft, the reciprocating bar D^2 , operated by the driving-shaft, the standard pivoted thereto, the clamping-jaws carried thereby, the levers connected to the clamping-jaws and operated by the 80 cams on the counter-shaft, the standard having the rigid jaw, the lever O' , having the movable jaw N' and operated by one of the cams on the counter-shaft, the reciprocating oscillating frame operated by the cranked 85 driving-shaft and having the bending arm or finger, the feed-rollers, and the cam to operate the pivoted standard, substantially as described.

7. The combination of the reciprocating 90 standard, the clamping-jaws carried thereby, the levers connected to said jaws to operate the same, and the shaft having the cams operating said levers, substantially as described. 95

8. The combination, with the reciprocating bar, of the standard pivoted thereon, the movable clamping-jaws carried by said standard and having the right-angled bars, the levers having the slots engaging said bars, and the 100 shaft having the cams operating said levers and the retracting-springs, substantially as described.

9. In a machine for making wire hinges, the combination of the reciprocating bar, the 105 standard pivoted thereon and having the movable clamping-jaws, the cam to move the standard laterally in one direction, the spring to move the standard laterally in the reverse direction, the movable frame having the bending-finger, the levers connected to the clamping-jaws, and devices to operate said levers, 110 substantially as described.

10. The combination of the two pairs of clamping-jaws, one pair being stationary and 115 the other pair relatively movable, the bending-arm to travel between the relatively-stationary jaws, and the levers and cams to close the said pairs of jaws in succession, said cams and levers being adapted to open the jaws simultaneously, substantially as described. 120

11. The combination of the wire-feeding devices arranged at right angles to each other with the relatively-stationary pair of clamping-jaws, the movable pair of clamping-jaws 125 adapted to traverse the former, and the bending-arm and operating devices, substantially as described.

12. In a machine for making wire hinges, the combination of the two pairs of clamping-jaws, one pair being relatively stationary and 130 the other pair relatively movable, the bending-arm to travel between the relatively-stationary jaws, and mechanism whereby said

jaws shall be closed in succession but opened simultaneously, as set forth.

13. In a machine for making wire hinges, the combination, with the wire-guides B', the 5 clamping-jaws N'S', and finger F³, of the hook G, which follows in rear of the finger F³ and engages the next succeeding portion of the wire that is fed forward through the guides B' and partly bends the same, for the purpose set forth.

14. In a machine for making wire hinges, the driving-shaft and counter-shaft geared thereto, in combination with the feed-rollers operated by the counter-shaft, the reciprocating bar D², operated by the driving-shaft, the clamping-jaws carried by the bar D², said jaws being operated by the counter-shaft, and the reciprocating oscillating frame operated by the driving-shaft and having the bending 20 arm or finger, as set forth.

15. In a machine for making wire hinges, the driving-shaft and the counter-shaft geared thereto, in combination with the reciprocating bar D², operated by the driving-shaft, the 25 clamping-jaws carried by the bar D² and operated by connections with the counter-shaft, and the reciprocating oscillating frame operated by the driving-shaft and having the bending arm or finger adapted to move between the opposing sides of the said jaws, as set forth.

16. In a machine for making wire hinges, the feed-rollers Y S and the guide B' for one wire a, in combination with the feed-rollers 30 K³ L³ for the other wire b, the moving guide-arm E³, having a finger adapted to come in contact with the intersecting portions of the wires, and the clamping-jaws, as set forth.

17. In a machine for making wire hinges, 40 the feed-rollers S Y and the guide B' for one wire a, in combination with the feed-rollers K³ L³ for the other wire b, and the moving guide-arm E³, having a finger adapted to come in contact with the intersecting portions of the wires, and the cutter I', to sever the wire a and leave the severed portion in the grasp 45 of the finger and the clamping-jaws, as set forth.

18. In a machine for making wire hinges, 50 the guide B' for one wire a, in combination

with the feed-rollers K³ L³ for the other wire b, the moving guide-arm E³, having a finger adapted to come in contact with the intersecting portions of the wires, the cutter I', to sever the wire a and leave the severed portion in contact with the finger, and the jaws S' N', between which the finger passes, the jaw S' being caused to move toward the rigid jaw N' and bend the severed portion of the wire a into the form of a staple, as set forth. 60

19. In a machine for making wire hinges, the guide B' for one wire a, in combination with the feed-rollers K³ L³ for the other wire b, the moving guide-arm E³, having a finger adapted to come in contact with the intersecting portions of the wires, the cutter G', to sever the wire a and leave the severed portion in the grasp of the finger, and the jaws S' N', between which the finger passes, the jaw S' being caused to move toward the rigid jaw N' and bend the severed portion of the wire a into the form of a staple, as set forth. 70

20. In a machine for making wire hinges, the moving arm or guide E³, having the bending-finger, combined with the jaws S' N', between which the arm or guide passes to bend the wire a, the jaws I² R², adapted to move 80 in front of the wire b and become engaged therewith and to bend the same, and the cutter carried by the guide-arm to sever the wire b, as set forth.

21. In a machine for making wire hinges, 85 the jaws N' S', between which the wire a remains clinched, and the jaws I² R², arranged at right angles to the jaws N' S' and adapted to move rearward under and over the jaws N' S' and serve to bend the severed portion 90 of the wire b in the bent portion of the wire a, thereby linking the said bent wires together, as set forth.

In testimony that I claim the foregoing as my own I have hereto affixed my signature in presence of two witnesses.

DAN L. HILL.
